BENJAMIN FRANKLIN CATHCART, OF FRESNO, CALIFORNIA.

ROTARY PUMP.

1,100,532.

Specification of Letters Patent.

Patented June 16, 1914.

Application filed April 30, 1913. Serial No. 784,556.

To all whom it may concern:

Be it known that I, BENJAMIN F. CATHCART, a citizen of the United States, and a resident of Fresno, in the county of Fresno 5 and State of California, have invented a new and Improved Rotary Pump, of which the following is a full, clear, and exact description.

The invention relates to improvements 10 in rotary pumps of the vertical type, and has reference more particularly to the casing structure for the pump.

An object of the invention is to provide 15 an inexpensive, simple and efficient rotary pump relieved of end thrusts.

A further object of the invention is to give to the liquid pumped a spiral motion by providing spirally directed inlets and outlets.

20 The invention consists of the construction and combination of parts to be more fully described hereinafter and fully set forth in the claims.

Reference is to be had to the accompanying 25 drawings forming a part of this specification, in which like characters indicate corresponding parts in all the views and in which:

Figure 1 is a vertical section on line 1—1, 30 Fig. 3, showing two superposed pumps embodying my invention; Fig. 2 is a section on line 2—2, Fig. 1; Fig. 3 is a cross section on line 3—3, Fig. 1; Fig. 4 is a cross section on line 4—4, Fig. 1; Fig. 5 is a section on line 5—5, Fig. 3; and Fig. 6 is a perspective view of the cylinder proper with the projections forming the passageways, and the whole forming a director.

Referring to the drawings, 10 indicates 40 the exterior tubular casing or shell inclosing a cylinder 11 concentric with the casing 10. The cylinder 11 is provided with a central opening at its lower end having the diameter of the cylinder, while the upper 45 end 12 of the cylinder is provided with an axial bore 14 and adjacent the bore a collar 13. The cylinder 11 is provided at its upper and lower ends with flange portions 15 extending from the exterior lateral surface of 50 the cylinder to the interior lateral surface of the casing 10. The upper flanges 15 are parallel to the lower flanges 15 but turned through an angle with reference to the lower flanges, so that the lateral ribs 16 connecting 55 the ends of the upper and lower flanges form spirals on the exterior lateral surface

of the cylinder, the ribs 16 fitting snugly against the inner lateral surface of the casing 10.

The upper and lower flanges 15 and the spiral ribs 16 form spiral lateral passageways open only at one end. Two of the oppositely disposed passageways are open at one end and the other two at the opposite end. The passageways open at the lower end communicate with the cylinder by means of an opening 17 provided in the lateral surface of the cylinder adjacent the upper flange 12. The spiral passageways open at the upper ends communicate with the cylinder by means of openings 18 formed in the lateral surface of the cylinder intermediate the opening 17 and the lower end of the cylinder. The openings 17 and 18 are formed between the ribs 16 and the width 75 of the openings is substantially equal to the spiral passageways formed by the spiral ribs 16. The cylinder 11, flanges 15, and ribs 16 form the director for the liquid when in place in the casing 10.

The cylinder 11 is secured to casing 10 by means of screws, or any other suitable means, engaging the flanges 15 and the casing 10. Positioned in the cylinder 11 is a rotor 19 formed of a plurality of fan-shaped 85 blades 20 rigidly secured to a vertical shaft 21. The lateral edges of the blades 20 are parallel to the axis of the shaft 21; and rigidly secured to the ends of the blades 20 are flanges 22 provided with central openings 90 23, the flanges and blades fitting snugly into the cylinder 11. The shaft 21 is bearing with its lower end in a spider plate 24 secured to the casing 10. The length of the blades of the rotor 19, including the flanges 95 22, is such that it extends from the lowermost end of the cylinder up to the opening 17 in the same, the length of the opening 18 in the cylinder being substantially equal to the distance between the flanges 22 of the 100 rotor. The shaft 21 passes through bore 14 into the delivery pipe 25 secured to the casing 10 through the upper closed end of the same, where a collar 26 is secured to the projecting end of the shaft. The collar 26 rests 105 against the upper end of the delivery pipe 25; and a cap 27 engages the collar 26 and the closed upper end of the delivery pipe 25 to prevent vertical motion of the shaft 21.

As shown in Fig. 1, two superposed pumps 110 are placed, in view of the fact that each pump can raise water 40 feet above its cen-

ter; and when it is desired to raise water to a higher level, a second pump is added for each additional 40 feet or fraction thereof. When the shaft 21 is caused to rotate by any means in the direction indicated in Fig. 4 the water enters into the cylinder through the lower end of the cylinder through the opening 23 in flange 22, also, the water is caused to pass through the spiral passageways having the opening at the lower end, through the inlet openings 17, through the upper opening 23 of the upper flange 22 into the cylinder. The liquid entering from both ends of the cylinder relieves the rotor from end thrusts. It will also be remarked that the liquid entering the upper end of the cylinder through the inlet opening 17 receives a spiral motion in the direction of the motion of the rotor. Similarly the liquid, forced by the blades 20 through the outlet openings 18, receives a spiral motion when forced through the passageways open at the upper end leading to the delivery pipe 25. The pitch of the spiral that will give a better efficiency for the raised water depends on the number of revolutions, the length of the cylinder, and also on the number of blades on the rotor. Due to the formation of the spiral passageways the liquid receives a spiral motion of a certain pitch, which helps the rotor to raise the liquid.

It can be easily seen that the casing and cylinder in the casing, with the passageways formed therein, can be cast in a single piece if desired.

Having thus described my invention, what I claim as new and desire to secure by Letters Patent is:

1. In a rotary pump, a casing; a cylinder in said casing having means on the lateral surface connecting it to the lateral surface of the casing and whereby spiral lateral passageways are formed, the adjacent passageways being open at opposite ends, said cylinder having an inlet through one end and, inlets in the lateral surface near the opposite end communicating with the spiral passageways which are open at the end opposite where the lateral inlets are provided, said cylinder having outlets in the lateral surface communicating with the other passageways; and a rotor in the cylinder having fan-shaped blades and flanges having a central opening secured to the end of said blade, said flanges fitting snugly into said cylinder.

2. In a rotary pump, a casing having a cylinder therein spaced from the casing, and means dividing the space intermediate the two into spiral passageways open at one end, the adjacent passageways being open at opposite ends of said cylinder, the cylinder having an inlet communicating with the passageway open at one end and an outlet communicating with the passageway open at the other end; a rotor in said cylinder having a

plurality of blades and flanged heads integral with the ends of the blades, said flange fitting snugly in the cylinder and having a central opening, the outlet of the cylinder being between said flanges and the inlets of 70 the same exterior of said flanges.

3. In a rotary pump, a casing; a director in said casing forming in combination with the casing a plurality of lateral spiral adjacent passageways each having an opening, 75 the adjacent passageways having the openings at opposite ends, said director having a cylinder therein having inlets communicating with the passageways open at one end, and outlets communicating with the passageways open at the opposite end; a rotor in said cylinder comprising fan-shaped blades, end flanges having a central opening integral with the ends of the blade, said flanges fitting snugly into the cylinder with the outlet lying between the flanges, and the inlet lying exterior of the same.

4. In a rotary pump, a casing; a director in said casing comprising a cylindrical tubular portion, open at one end, having flanged ends and lateral spiral ribs connecting the flanges of the opposite ends, said flanges and ribs contacting with said casing and forming therewith spiral passageways each opening at one end, the adjacent passageways having the opening at opposite ends, said director having an inlet in the open end of said cylindrical portion and lateral inlet openings near the opposite end of the same below the flange portions at the said end, 100 thereby the said inlet openings communicate with the spiral passageways open at the opposite end, said director having lateral outlets intermediate the end inlets entering the passageway formed by said lateral ribs and the flanges adjacent the end inlet of the director; and a rotor in said cylindrical portion of the director comprising fan-shaped blades, and end flanges having a central opening, integral with the end of the 110 blades, each of said blades having the edge parallel to the axis of the rotor, and with said flanges fitting snugly into the cylinder of the director with the said outlets lying between the flanges and the inlets lying exterior of the same.

5. In a rotary pump, a casing having a cylinder therein spaced from the casing and means dividing the spaces intermediate the two into spiral passageways open at one end, the adjacent passageways being open at opposite ends of said cylinder, the passageways open at the same end forming an inlet to said cylinder, the passageways open at the other end of the cylinder forming the outlet 125 from the same; and a rotor in said cylinder.

6. In a rotary pump, a casing having a cylinder therein, said cylinder having lateral spirally-directed inlets intermediate said casing and cylinder, and also lateral, spirally- 130

directed outlets therebetween; and a rotor in said cylinder.

7. In a rotary pump, a double-wall casing having means between the walls forming spiral passageways, the adjacent passageways being open at opposite ends of said casing, said passageways forming inlets and outlets for the inner part of said casing; and a rotor in the inner part of said casing.

10 8. In a rotary pump, two concentric tubular members; means between said tubular members forming lateral, spiral passageways therebetween open at one end, the ad-

jacent passageways having the opening at opposite ends of said member, said passageways forming inlets and outlets for said inner member; and a rotor in said inner member.

In testimony whereof I have signed my name to this specification in the presence of 20 two subscribing witnesses.
